Inventor,
A. M. Plaisted.

UNITED STATES PATENT OFFICE.

HAROLD M. PLAISTED, OF GRANITE CITY, ILLINOIS, ASSIGNEE TO THE WILLIAMS
PATENT CRUSHER & PULVERIZER CO., OF ST. LOUIS, MISSOURI, A CORPORATION
OF MISSOURI.

PNEUMATIC SEPARATING SYSTEM.

1,272,311.

Specification of Letters Patent.

Patented July 9, 1918.

Application filed February 23, 1918. Serial No. 218,645.

To all whom it may concern:

Be it known that I, HAROLD M. PLAISTED, a citizen of the United States, residing at Granite City, in the county of Madison and 5 State of Illinois, have invented certain new and useful Improvements in Pneumatic Separating Systems, of which the following is a specification.

This invention relates to certain new and 10 useful improvements in pneumatic separating systems, being especially applicable to metal and gravel catchers in feed grinding systems. The peculiarities of my invention will be hereinafter described and claimed.

15 The object of my invention is to regulate the quantity and velocity of air admitted to the suction side of a fan, in order to vary its action on the feed material and contained foreign matter, such as metal and 20 gravel.

In the accompanying drawing on which like reference letters indicate corresponding parts,

Figure 1 represents a grinder and a pneumatic feed separating system embodying my 25 improvements; and Fig. 2, an enlarged view of a part of such system.

A designates a grinder and casing with bearings for a shaft B, rotated by a pulley 30 C, and having a flywheel fan and casing D, connected by pipe E to the bottom of the grinder. F is a horizontal feed pipe connected to the fan through the grinder, and G a rectangular vertical pipe extension with 35 its lower end open. A side opening in said vertical pipe is provided with a lateral hopper H with a slanting bottom h, and a regulating valve I, preferably automatic by which the feed material is admitted from 40 a chute J connected to a receiving hopper K. The flywheel fan, or other source of suction, causes a strong current of air to enter the open end of the pipe G and carry the feed alone upward and over through 45 pipe F to the grinder, then through pipe E to the fan, and thence it is blown to a collector (not shown). Along with the feed proper taken in by the receiving hopper K there is often found sand, gravel, 50 washers, buckles, nails, screws, nuts, bolts, miscellaneous iron and other foreign matter that will fall out of the bottom end of the pipe G when the air suction is properly regulated. An air inlet, such as a slip sleeve 55 L over an opening M in the pipe F, will

admit air above the lateral feed hopper H, and thus lessen the suction in the pipe G; for some light feed material this regulation is sufficient to effect the separation of the feed itself from foreign matter, but for 60 other feed material it is desirable to regulate the air inlet below the lateral hopper. A slide valve O, operated by a handle P, or otherwise, is mounted snugly between the bottom h and a guide Q, so as to form a 65 continuation of the slanting bottom of the hopper H. At the lower end is a depending apron R, hinged or otherwise pivoted thereto, and having a coil spring S, or other means that tends to keep the lower edge r 70 of said apron in sliding contact, against one side of the pipe G, in any adjusted position of the slide valve O. Dashed lines in Fig. 2 indicate such adjustment of the valve and its apron. A thumb-nut T, serves to 75 maintain the slide valve in position. The apron deflects the air current past the lower edge of the valve without forming a pocket or eddy below the same, whatever the position of the valve. The velocity of the entering air current is increased under uniform fan power, according as the opening is lessened, since the fan seeks to obtain its 80 full capacity of air; this increased velocity with less quantity of air, facilitates handling other varieties of feed and foreign matter mixed.

Furthermore, this slide apron valve in conjunction with the sleeve valve,—one located above the lateral feed inlet, and the other below it,—gives a finely graduated 85 control of both the quantity and the velocity of the air current, that allows its adaptation to a wide range of variety and condition of the feed material supplied to 90 the system.

While I have shown my improvements in connection with a flywheel fan and a grinder, I do not limit my invention to the construction and arrangement shown. 100

I claim:

1. In a pneumatic separating system, the combination with a vertically positioned pipe, subject to an upward air suction having a regulatable feed inlet at one side, and 105 a downwardly inclined hopper bottom communicating with said feed inlet, of a slide valve located below and parallel to said bottom, to deliver the gravitating feed and foreign matter off its bottom edge, and 110

extensible into said pipe to vary the air velocity past said edge, and an apron pivotally supported by the bottom edge of the slide, inclined downward and backward to a sliding engagement with the side wall of said pipe, substantially as described.

2. In a pneumatic separating system the combination with a vertically positioned pipe subject to an upward air suction, having a regulatable feed inlet at one side, and a downwardly inclined hopper bottom, communicating with said feed inlet, and an air inlet valve above the feed inlet to lessen the air suction and mix air with the passing feed, of an inclined slide valve mounted below said bottom to form a continuation

thereof, a depending backwardly inclined apron pivoted to the bottom edge of the slide valve, with its lower edge in slidable contact with one side of said pipe, whereby 23 is provided an air inlet valve above the feed inlet to vary the quantity of air sucked in, and an air cut off valve below the feed inlet to vary the velocity, whatever the quantity of air in said system. 25

In testimony whereof I have affixed my signature in the presence of two witnesses.

HAROLD M. PLAISTED.

Witnesses:

TALETA MICHAELIS,
W.M. G. WEBER.
